(57) **CLAIM**

The ornamental design for a crossbow scope, as shown and described.

DESCRIPTION

FIG. 1 is a front perspective view of a crossbow scope according to the present invention;

FIG. 2 is a rear perspective view of the crossbow scope;

FIG. 3 is a left side view of the crossbow scope;

FIG. 4 is a right side view of the crossbow scope;

FIG. 5 is a rear view of the crossbow scope;

FIG. 6 is a front view of the crossbow scope;

FIG. 7 is a top view of the crossbow scope; and,

FIG. 8 is a bottom view of the crossbow scope.

The broken lines shown in the drawings represent portions of the crossbow scope that form no part of the claimed design.
